ABDOMINAL SUPPORT

William Wagenseil, New York, N. Y.

Application March 13, 1934, Serial No. 715,259

6 Claims. (Cl. 128—96)

This invention relates to an abdominal support. It is especially useful in the treatment of cases of visceroptosis, although it may be used in other cases. Instead of using a pad with a fixed bulge, my pad is constructed to permit adjustment of the amount of the bulge or protuberance. The bulge is at the lower part of the pad with its upper part sloping forwardly and upwardly so as to provide upward support for the abdomen. Said bulge is made adjustable to lift up the abdomen as much as needed by the wearer.

While my support is primarily designed for causing upward pressure on the lower part of the abdomen, it may be used on other parts of the body where its action would apply.

A further object is the provision of ball and socket joints for universal mounting of the body springs upon the pad.

Other objects and advantages will become apparent upon a further study of the specifications and drawing, in which

Fig. 1 is a perspective rear view of the abdominal support.

Fig. 2 is a rear elevation of the pad with the leather cover partly lifted to show the movable bulge plate, said plate being partly broken away to show a guide sleeve. Fragments of the body springs are also shown.

Fig. 3 is a section taken along the line 3—3 of Fig. 2, the leather cover being in closed position and the spring omitted. In this figure the bulge plate is but slightly spaced from the front plate.

Fig. 4 is a section similar to Fig. 3 except that the bulge plate is spaced a greater distance from the front plate.

Fig. 5 is a plan view taken along the line 5—5 of Fig. 3, a portion of the socket connection for one of the body springs being broken away and the leather cover separated at the bottom of the pad but not folded back as in Fig. 2.

Fig. 6 is a perspective view of the bulge plate shown removed from the pad.

Fig. 7 is a partial section and elevation of the socket connection taken along the line 7—7 of Fig. 5, a portion of the rounded head being broken away to show the shank of the ball member in the slot, and

Fig. 8 is an elevation of the end of the body spring by itself shown removed from the pad.

The abdominal support comprises a pad 8 and body springs 9, having back pads 10.

Pad 8 has a metallic front plate 11 which is convexed to the front, said convexity being chiefly

about a vertical axis. Projecting from the rear and located near the bottom of front plate 11 are a pair of guide sleeves 12. Between said sleeves is located an adjusting screw or shaft denoted in its entirety by the numeral 13. The slotted head 14 of the screw projects in front of front plate 11 and in front of the front chamois covering 15, the shank of screw 13 passing through suitable holes provided in plate 11 and in said covering which is pasted to the front of front plate 11. Said screw is free to rotate in said holes. Fixedly mounted on screw 13, is a collar 16 having sliding contact with the rear of front plate 11. The threaded rear end of the shank of screw 13, engages the internal threading of sleeve 17, which projects forwardly from metallic bulge plate 18. On either side of sleeve 17 and opposite guide sleeves 12 are pins 19 which are adapted slidably to engage said guide sleeves. While the front and the bulge plates 20 are preferably of metal, other stiff materials, such as pyroxylin, might be used.

Bulge plate 18 is convexed toward the rear, about a horizontal axis. The side edges of said plate are in addition curved toward the front 25 and the plate as a whole slightly convexed toward the front about a vertical axis. Above the region of maximum rearward protuberance plate 18 extends for a greater distance than below. The convexity of plate 18 about a horizontal axis 30 above said region of maximum protuberance flattens out.

A chamois covering 20 backed with cotton felt 25 is provided for the back of pad 8 passing over bulge plate 18. Back covering 20 and 25 35 is fastened to front chamois covering 15 all around the edges of front plate 11 by suitable means, such as stitching 30. No layer of cotton felt is provided for the front covering 15. Back chamois covering 20 is provided with suitable slack to allow for various settings of bulge plate 18 with respect to front plate 11. The coverings are preferably of chamois, but other suitable soft flexible material might be used as cotton cloth.

The body springs are fastened to front pad 8 by means of ball and socket joints, the left hand one in Fig. 5 being denoted in its entirety by numeral 26. Each joint comprises a rounded head 21 at the forward end of a shank 27 fastened to front plate 11. The socket portion comprises two parts, one part having a body portion 22 and a cup shaped end 23 and the other part being cup shaped end 25 of spring 9. Body portion 22 is fastened by means of screws 55

31 to spring 9. Spring 9 has the usual chamois covering 24. End 23 is provided with a slot so that it can be mounted over the shank of rounded head 21. End 25 is also provided with 5 a slot. The slot in end 25 gives more room for rounded head 21. Instead of having the cupped end 25 in front of rounded head 21, it might come against the rearward surface of head 21, with cupped end 23 to the front. But my preferred 10 construction is as shown in the drawing as it gives a neater appearance.

By turning screw 13 in one direction, bulge plate 18 is drawn close toward front plate 11, as in Fig. 3. By turning said screw in the opposite 15 direction bulge plate 18 is spaced farther away from front plate 11, as in Fig. 4. The more bulge plate 18 is spaced from front plate 11, the greater will be the lifting action on the abdomen of the wearer of the support. The fact that the universal joints 26 of body springs 9 are located 20 above the region of maximum protuberance of bulge plate 18, plays a part in the lifting action. The front pad is in effect a lever, fulcrumed about the horizontal axis of rotation of the pad, which 25 is along a horizontal line passing through said joints. The upper arm of the lever, which is the portion of pad 8 above said horizontal axis is of greater length than the distance from said axis to the region of maximum protuberance below, so 30 that the pressure of the abdomen on the upper part will cause said region of maximum protuberance to swing upward with a greater pressure.

While the claims specify my device as an abdominal support, they are intended to be broad 35 enough to cover my device where used on other parts of the body in such situations where its action will apply.

I claim:—

1. A front pad for an abdominal support comprising a front plate, a pair of spaced rearwardly extending guide means upon said plate, a bulge plate, a pair of forwardly extending guide means 40 slidably engaging said former means, a shaft rotatably mounted in an opening provided in said front plate, said opening being located immediate 45 of said rearwardly extending guide means, the rear portion of said shaft being threaded, the front end of said shaft extending in front of the front plate and having an enlarged head there- 50 on for enabling the shaft to be manually rotated and to prevent rearward axial motion of said shaft, means on said shaft preventing forward axial motion of the shaft and an internally threaded sleeve extending forward from the bulge plate, the rear portion of said shaft being threaded 55 into said sleeve whereby rotation of said shaft varies the distance between said plates.

2. A front pad for an abdominal support comprising a front plate, a pair of spaced rearwardly 60 extending guide means upon said plate, a bulge plate, a pair of forwardly extending guide means upon said bulge plate slidably engaging said former means, a member rotatably mounted in an opening provided in said front plate, said 65 opening being located intermediate of said rearwardly extending guide means, the front end of said member extending in front of the front plate for enabling said member to be manually rotated, the front portion of said member overlapping the edge of said hole both in the front and in the rear of the front plate to prevent axial motion of said member, and a piece on said bulge plate 70 extending forward a portion of the distance be-

tween the two plates opposite said piece, said member and said piece being in threaded engagement whereby rotation of said member varies the distance between said plates.

3. A front pad for an abdominal support comprising a front plate, a bulge plate located to the rear of the front plate, a pair of spaced guide means extending between said plates, each of said guide means comprising two parts, one of said parts being a sleeve and the other of said 10 parts being a pin slidably mounted in said sleeve, one of said parts being fastened to the rear of the front plate and the other of said parts being fastened to the front of the bulge plate, a screw rotatably mounted in a hole provided in said 15 front plate, said hole being located intermediate of the guide means, the head of said screw coming in front of the front plate, a collar fixed upon said screw at the back of said front plate, and an internally threaded sleeve fastened to the 20 bulge plate extending forward therefrom a portion of the distance between the plates at the sleeve, the rear portion of the screw engaging the threads of the sleeve, whereby rotation of said screw varies the distance between the 25 plates.

4. A front pad for an abdominal support comprising a front plate of substantially the full extent of the pad, a bulge plate, convexed rearwardly about a horizontal axis and being of substantially less height than the front plate, a pair of spaced rearwardly extending guide means upon the front plate on its lower portion, a pair of forwardly extending guide means upon the bulge plate slidably engaging said former means, an envelope covering both plates having a front portion closely fitting to the front of the front plate and a flexible rear portion provided with slack extending to the rear of both plates, a member rotatably mounted in an opening provided in said front plate, said member extending in front of the front plate through the envelope for enabling said member to be manually rotated, the front portion of said member overlapping the edge of said hole both in the front and in the rear of the front plate to prevent axial motion of said member, and a piece on said bulge plate extending forward, said member and said piece being in engagement, the rotation of said member varying the distance between the plates.

5. In an abdominal support comprising body springs and a front pad having a front plate, a universal mounting for attaching said springs to the pad having a member with a shank and a rounded head, said shank being attached to the plate, a cupped end on the spring and a piece having a body portion and a cupped end, the body portion of said piece being fastened to the spring, holding the cupped end of the piece opposite the cupped end of the spring, one of said 60 ends slidably engaging the forward surface of said rounded head and the other of said ends slidably engaging the rearward surface of said rounded head, said latter end being provided with a slot through which said shank passes.

6. In an abdominal support comprising body springs and a front pad having a front plate, a universal mounting as claimed in claim 5 in which the cupped end engaging the forward surface of the rounded head is slotted substantially 70 opposite the slot of the cupped end engaging the rearward surface of the rounded head.

WILLIAM WAGENSEIL.
